CLAIM

The ornamental design for a clip, as shown and described.

DESCRIPTION

FIG. 1 is a top perspective view;

FIG. 2 is a bottom perspective view;

FIG. 3 is a front elevation view thereof; the back elevation view is symmetrical to the front elevation view;

FIG. 4 is a right side elevation view thereof;

FIG. 5 is a left side elevation view thereof;

FIG. 6 is a top plain view thereof;

FIG. 7 is bottom plain view thereof;

FIG. 8 is an enlarged view of a portion indicated by arrows 8-8 in FIG. 1;

FIG. 9 is an enlarged view of a portion indicated by arrows 9-9 in FIG. 2;

FIG. 10 is an enlarged view of a portion indicated by arrows 10-10 in FIG. 3; and,

FIG. 11 is an enlarged view of a portion indicated by arrows 11-11 in FIG. 6.

The broken lines shown in the drawings represent unclaimed portions of the clip and form no part of the claimed design. The dot-dash-dot broken lines in the drawings define the bounds of the claim and form no part thereof.

1 Claim, 4 Drawing Sheets
